UNITED STATES PATENT OFFICE.

WALLACE APPLETON BEATTY, OF NEW YORK, N. Y., ASSIGNOR, BY DIRECT AND MESNE ASSIGNMENTS, TO GEORGE W. BEADLE, OF NEW YORK, N. Y.

ARTIFICIAL FILAMENT AND OTHER PRODUCT.

1,156,969.

Specification of Letters Patent.

Patented Oct. 19, 1915.

No Drawing.

Application filed January 3, 1913. Serial No. 740,079.

To all whom it may concern:

Be it known that I, WALLACE APPLETON BEATTY, a citizen of the United States, residing at New York, in the county of New York and State of New York, have invented certain new and useful Improvements in Artificial Filaments and other Products; and I do hereby declare the following to be a full, clear, and exact description of the invention, such as will enable others skilled in the art to which it appertains to make and use the same.

This invention relates to filaments especially adapted for the making of artificial silk and other fabrics, and has for its object to produce products of this nature which will be water-proof, as well as non-inflammable, strong and tenacious, and will therefore, be more efficient in use than those heretofore proposed.

To these ends the invention consists in the novel filaments and products made from a mixture of cellulose acetate and dioxy-diphenyl-dimethyl-methane, all as will be more fully hereinafter disclosed and particularly pointed out in the claims.

In order that the invention may be more clearly understood, it is said:—In my prior application #702,046, filed June 6, 1912, entitled "Artificial gums and process of producing the same," I have disclosed and claimed a new gum and method of making it, which method, when briefly stated, consists in forming a crystalline product from a mixture of acetone and phenol to which is added a small quantity of acid, in order to produce a compound, which I believe to be dioxy-diphenyl-dimethyl-methane. In said application, this compound is then further acted upon by formaldehyde, in order to produce a further product constituting a new gum, but the latter is not always used in this invention. This compound dioxy-diphenyl-dimethyl-methane is of a crystalline form, and soluble in alcohol, ether, acetone, glacial acetic acid, amyl alcohol, amyl acetate and acetylene-tetra-chlorid, or mixtures of these. Accordingly, in making artificial silk, or other filaments out of this said compound and cellulose acetate, I preferably provide a mixture containing say 25 parts by weight of the said dioxy-diphenyl-dimethyl-methane

and 75 parts by weight of cellulose acetate, this mixture is then dissolved, preferably in acetone, to the proper consistency, and I force the solution through the usual capillary orifices now employed in making filaments for artificial silk, and recover the said filaments in any suitable liquid in which the filaments are not soluble, such for example, as benzene, or in any other desired and well known manner.

The filaments thus made, as in fact the compound substance, when otherwise produced, is found to be hard and tenacious, transparent and flexible, insoluble in water, very resistant to moisture, and non-inflammable in the sense that it will only burn when kept constantly in the flame.

The filaments when thus, or otherwise, produced, may be combined into larger threads, or they may be of a sufficient size to be used as threads themselves, and are finally woven into the desired fabric in manners well known.

After a fabric is thus made, for some purposes, such for example, as tent cloths, I may coat the fabric in the known way, with a thin solution of the mixture in order to make it more water proof, stiffer, or less permeable to the air, or I may dip the entire fabric into a thin solution of the mixture for the same purposes.

Not only may I make entire fabrics out of the filaments thus proposed, but I may take ordinary fabrics, such as cloth, paper, etc., and soak the same in well known ways, in a solution of this mixture, or I may apply the said mixture to the said fabrics as a coating very much as varnish-like substances are now applied to such fabrics for the production of imitation leather, leatheroid, and for a host of other purposes, as will be mentioned below.

In some cases, I may load the fabric with alum, cellulose acetate, or other suitable substances to decrease their inflammability and to give other well known properties thereto.

Not only may I employ this mixture in a state of solution for the treatment of fabrics, but I may also use it as a dressing for leather. In this use, the leather is suitably prepared, as for example, in the manner it is now prepared for the reception of the well known

pyroxylin leather dressing, and I may apply the mixture to the leather with a brush, by dipping, or by other well known means, whereupon the leather may be passed between rollers and otherwise treated, when it will be found to have a tenacious, hard water-proof coating which gives it a bright appearance and is found to be exceedingly durable.

10 Leather may even be impregnated with my new mixture in order to increase its wearing qualities, and to provide a flexible water-proof material of this nature. This impregnation is especially suitable for sole leather, insoles, etc., and in order to render the leather more flexible, I may reduce the quantity of cellulose acetate and increase the quantity of the dioxo-diphenyl-dimethyl-methane. A good mixture would consist 20 of say equal parts of these substances.

Not only may I apply this mixture to fabrics, leather, etc., as above stated, but I may even make patent leather therefrom. In such case, the leather is prepared in a 25 manner similar to, or the same, as it is now prepared for the reception of the present pyroxylin coating; my mixture is applied thereto as by a brush, or by other means, and the leather is finished in a manner well 30 known to those skilled in this art.

A further application of my new mixture is in the production of substitutes for the well known pyroxylin artificial leathers in general. As is well known, these leathers 35 are in great demand at present, and it is very desirable to find a cheaper and better material to furnish the coatings which are employed.

It is further well known that when the 40 present pyroxylin coating is subjected to the wear and tear of use and especially to the moisture with which it comes in contact, it undergoes a decomposition which liberates to a greater or less extent, its contained nitric acid, which results in a breaking up of the coating itself, as well as an injury to the cloth, or other substances forming the body of the leather.

It, of course, is further well known to be 50 highly inflammable, thereby necessitating the loading of the material with non-inflammable substances.

My compound, on the other hand, is subject to no such disadvantages and it furnishes at once a hard, absolutely water-proof, and a non-inflammable coating having 55 a high polish and great wearing qualities.

In fact, by properly coating fabrics of various kinds or impregnating the same with my new mixture or compound, subjecting them to the action of rollers to the calendering, and other processes to which leatheroid, 60 artificial leathers, and like substances are 65 now commonly subjected, I produce a prod-

uct which is at once much less expensive and far more durable than are any of the like products now in use.

In many cases, it is desirable to pass the article coated with the mixture with or 70 without a filling material between rollers in order to firmly compress the same in the manner now well known in producing similar materials with other substances.

I may not only make threads or yarns or 75 filaments from the mixture itself, but I may employ silk, cotton, linen, or other threads or yarns, and impregnate the same with the mixture by passing said threads or yarns through a bath containing the mixture dissolved to the proper consistency. These said 80 impregnated threads or yarns may then be woven into suitable fabrics or used for other purposes.

My mixture is further useful as a malleable 85 glass in that it is transparent, tenacious, water proof, and is especially adapted for the making of automobile shield, window panes in carriages, wagons, cars, etc. It is also useful for making lanterns aboard ship, 90 which are subjected to the concussions of gun fire, or for making any other glass-like articles which are in constant danger of being broken. In making these glass-like articles, the mixture is preferably flowed on to 95 flat sheets, such as glass, into sheets of a suitable thickness, whereupon it may be subjected to the action of rollers and smoothed out. The surfaces may then be polished in a manner similar to the polishing of glass 100 surfaces well known to those skilled in the art, whereupon it will be found to have a high polish, to be transparent and well adapted for its purpose. The glass-like sheets may also have incorporated therein 105

the usual wire reinforcements that are now found in reinforced glass, in which condition it is especially adapted for the roofs of vaults, hot houses, and other places. Such sheets may further be colored by dyes, or by 110 other means, and the material made into celluloid articles. These said celluloid articles may be further reinforced or strengthened by wire material molded therein. In fact, 115

the new mixture is well adapted for celluloid articles in general in that it may be molded, colored, dyed, or otherwise finished into any desired shapes that celluloid articles now have, and such articles will have 120 the very desirable property of being non-inflammable while they will also be less expensive to produce. In making up these celluloid articles, the mixture is brought to a suitable consistency, suitable dyes are mixed therewith, or other coloring matter, and in 125 fact, suitable fillers may be also incorporated therewith, as is usually done in making such articles.

The procedure in making these various articles is in all respects similar, if not iden- 130

tical, with the making of corresponding articles out of celluloid, and other plastic substances.

In addition to the above uses of this mixture, articles that are now usually made from hard rubber may be likewise produced from this new compound and mixture.

In making substitutes for hard rubber articles out of the mixture, if they are to have a dark or black color, suitable coloring material, such as lamp black is readily incorporated with the mixture, the material is molded, or otherwise formed, in the proper shape and the articles may be cut or otherwise fashioned, precisely as hard rubber is now worked.

A further useful article may be made from my new mixture, in the form of a bag to contain explosive charges for ordnance. The present powder bags used for this purpose are made of silk, which has the objection, not only of being porous, and thereby permitting the gases of the smokeless powder to escape, but they are also inflammable and liable to cause their contained powder to explode when coals of fire, or other burning objects, are accidentally dropped on the outside of the bag.

In treating powder bags with my new mixture, I coat the outside of the silk bag with a layer of the solution which is of sufficient thickness to prevent sparks, or other ignited objects, from penetrating to the powder when accidentally dropped thereon, and at the same time, I render the silk itself non-permeable to the escaping gases, and thereupon keep the powder air tight. This has the advantage of making the charge more uniform when exploded, and therefore gives increased accuracy to the shot when fired.

Of course, the new mixture, when dried or molded, is well adapted for the making of buttons, combs, and other articles of personal wear which are now usually made from pyroxylin compounds, and has the further advantage of being non-inflammable and inodorous. It is further well adapted for the fixing of the bristles of brushes, such as tooth brushes, shaving brushes, etc., in their holders, which holders may be made of the same material or of other substances, as may be desired.

It is further well adapted for the making of artificial ivory, horn, tortoise shell, and other substitutes, which are now usually made out of pyroxylin or celluloid compounds.

In producing these various articles, my mixture is first suitably colored by dyes, or other coloring matter, and it is treated in all manner, or very similar, as the corresponding celluloid articles would be treated.

My mixture is in addition to the above uses, well adapted for insulating purposes

in general. It is found to have a very high resistance, and being insoluble in water and very resistant to moisture, it is well adapted for insulating purposes, and has the further advantage of being non-inflammable.

My mixture further makes a very useful lacquer. For this purpose, it is made of a suitable consistency and may be even mixed with other gums for special purposes. In order to make this lacquer, it is only necessary to dissolve the dioxy-diphenyl-dimethyl-methane mixed with cellulose acetate in a suitable solvent, such as acetone or acetone mixed with methyl alcohol, and bring the mixture to the proper consistency whereupon it may be applied with a brush, or in any other manner. In order that the lacquer may be unusually hard, I may likewise dissolve my novel gum mentioned in the first portion of this specification, in the acetone, or other suitable solvent, and mix the same in suitable proportions with the lacquer. A good mixture is made from adding say five per cent. of the gum up to twenty-five or thirty per cent. thereof, according to the uses to which the lacquer is to be applied. I have further found that if the dissolved gum is made to have an acid reaction by adding acid thereto, it will go into its hard and insoluble condition without having to go through the heating stages which are described in my said pending application above, and therefore, for many purposes in making this lacquer I prefer to add sufficient acid to the solution of gum to give it this acid reaction.

In making many of the articles above disclosed, and especially the powder bag, or other articles to which it is especially desired to impart a non-inflammable character I prefer to employ an acid solution of my gum as an outer coat or coating for the article in question. In fact, after a silk powder bag is coated with my mixture, I then preferably apply a coating of the acid solution of the gum over the same, and thereby secure an exceedingly non-inflammable powder bag.

The same treatment is given to the articles which are provided with my mixture as an insulating compound. That is to say, when I coat a wire, for example, with my mixture as an insulating compound for many purposes. I prefer to pass the coated wire through a bath containing my acidulated solution of gum in order to give it an outer coating of a hard enamel-like character, which is non-inflammable and very durable.

In addition to the above, I may add to the mixture of dioxy-diphenyl-dimethyl-methane and cellulose acetate a greater or less proportion of the gum solution for a large number of the purposes above mentioned, in order to give them greater hardness, greater resistance to chemicals in gen-

eral and for other purposes, as will be obvious to those skilled in the art.

Not only may I employ a mixture of dioxy-diphenyl-dimethyl-methane and cellulose acetate for the above purposes, but for many purposes I may employ homologues of phenol, as well as of acetone for the preparation of mixtures with cellulose acetate, all as will be obvious to those skilled in this art. In fact, it is further obvious that organic chemists and others skilled in this art, may vary the details of my procedure without departing from the spirit of my invention, and therefore, I do not wish my invention to be limited to the said disclosure except in those cases in which it would positively require invention to depart therefrom. In fact, I believe my invention to be broadly new and myself to be entitled to all of the equivalents which the present knowledge of those skilled in the art would produce.

Further, in my copending application #694274 filed April 30, 1912, and entitled "Plastic compound and process of making same," I have disclosed a compound consisting of a cellulose ester and a condensation product of acetone or its homologues with phenol or its homologues. That is to say, I have disclosed a plastic substance composed of dioxy-diphenyl-dimethyl-methane and a nitro-cellulose, preferring to use about eighty parts of nitro-cellulose and twenty parts of dioxy-diphenyl-dimethyl-methane dissolved in a suitable solvent, such as amyl acetate; or this latter solvent mixed with acetone. The product produced by this mixture and disclosed in said application is a transparent or translucent substance strong and tenacious, but more inflammable than is the product produced by the mixture of cellulose acetate and the dioxy-diphenyl-dimethyl-methane above mentioned. It is obvious, however, that each of the products mentioned above as made of this last named mixture may be duplicated with a mixture made from dioxy-diphenyl-dimethyl-methane and cellulose nitrate. It is not necessary to repeat the steps or process of making each of these several products, but in producing the same, it is said that these said steps are well known in the art of producing these various products and are substantially the same as the steps outlined above in connection with said products.

Accordingly, I wish it to be understood that I do not limit this application to the use of cellulose acetate in the mixture, but

I wish it to also cover the use of nitro-cellulose, preferring for most purposes, the 60 tri-nitrate.

Not only may I duplicate the articles above mentioned with a mixture containing cellulose nitrate, but I may also load or mix the mixture of cellulose nitrate and 65 dioxy-diphenyl-dimethyl-methane with camphor, or camphor substitutes. This makes a very beautiful transparent material which may be substituted for celluloid, and may be worked and handled precisely as, or substantially, as celluloid is now worked in the various arts.

It further can be utilized in making each of the above products, and therefore, I want it distinctly understood that this application likewise covers the use of camphor in connection with my dioxy-diphenyl-dimethyl-methane and cellulose nitrate.

In making up plastic compounds employing camphor, I preferably mix the camphor and the dioxy-diphenyl-dimethyl-methane in about equal proportions, and then mix the two with the cellulose nitrate, but, of course, the ratio proportions may be varied without departing from the spirit of my invention. A good mixture is composed of say seventy-five per cent. tri-nitro-cellulose and twelve and one-half per cent. each of camphor and dioxy-diphenyl-dimethyl-methane. This mixture is dissolved in the 90 same solvents as those mentioned above.

What I claim is:—

1. The herein described new article of manufacture consisting of a woven fabric comprising threads containing as an essential element a mixture of dioxy-diphenyl-dimethyl-methane and cellulose acetate, substantially as described.

2. The herein described new article of manufacture consisting of a thread adapted to be woven into a fabric and containing as an essential element a mixture of dioxy-diphenyl-dimethyl-methane and cellulose acetate, substantially as described.

3. The herein described new article of manufacture consisting of a fiber adapted to be twisted into a thread and containing as an essential element a mixture of dioxy-diphenyl-dimethyl-methane and cellulose acetate, substantially as described.

In testimony whereof, I affix my signature, in presence of two witnesses.

WALLACE APPLETON BEATTY.
